P. J. FITZGERALD,

BATH SPRAY.

APPLICATION FILED MAR. 11, 1920.

1,342,994.

Patented June 8, 1920.

UNITED STATES PATENT OFFICE.

PATRICK J. FITZGERALD, OF TORRINGTON, CONNECTICUT, ASSIGNOR TO THE FITZ-
GERALD MFG. COMPANY, OF TORRINGTON, CONNECTICUT, A CORPORATION OF
CONNECTICUT.

BATH-SPRAY.

1,342,994.

Specification of Letters Patent.

Patented June 8, 1920.

Application filed March 11, 1920. Serial No. 365,021.

To all whom it may concern:

Be it known that I, PATRICK J. FITZ-
GERALD, a citizen of the United States, re-
siding at Torrington, in the county of Litch-
field, State of Connecticut, have invented
5 certain new and useful Improvements in
Bath-Sprays, of which the following is a
description, reference being had to the ac-
companying drawing and to the figures of
10 reference marked thereon.

This invention relates to bath sprays, and
more particularly to a combined bath spray
and massage device.

One of the objects of this invention is to
15 provide a device of the character described
in which the perforated face plate of the
spray head is provided with a plurality of
detachable massage members.

Another object of this invention is to
20 provide the face plate of the spray head
with a plurality of massage members ar-
ranged about the spray openings to produce
the most advantageous spraying and mas-
saging effects.

25 Still another object of this invention is to
combine with a spray head of the charac-
ter described, a soap container arranged
within the spray head in the path of the
water inlet whereby the spray is given a
30 soapy quality.

These and other objects will in part be
obvious and will in part be hereinafter more
fully disclosed.

In the accompanying drawings:—
35 Figure 1 is a perspective view looking
down on the top of the device;

Fig. 2 is a side section therethrough, the
massage nipples being shown in full;

Fig. 3 is a bottom view showing the ar-
40 rangement of the massage nipples and the
spray openings on the face plate;

Fig. 4 is a detail view of a modification
of one of the massage nipples, and

Fig. 5 is a modification of the spray head
45 showing one means for locating the soap
container within the same.

In general, the invention comprises a
spray head provided with a face plate and
a back plate forming a closed water cham-
50 ber having a water inlet. The face plate
is provided with a centrally located remov-
able massage member and a plurality of
similar concentrically arranged massage
members. Intermediate these central and

concentric massage members, the face plate 55
is provided with a series of spray openings,
whereby the device may be used to massage
the body of the user while permitting the
free discharge of the water from the spray
head. 60

Referring more particularly to the accom-
panying drawings, the bath spray includes
a spray head comprising a face plate 1, to
which is secured, in any desirable manner,
a back plate 2 having the dome 3. These 65
front and back plates form a closed water
chamber proper with a water inlet 4. In
the present instance, the edge of the back
plate 2 is crimped about the annular edge
of the face plate. The inner side of the face 70
plate is preferably formed with a centrally
raised boss 5 or provided with a threaded
opening for the purpose of receiving the
threaded stem 6 of the central massage
member 7 hereinafter described, and pref- 75
erably concentrically arranged about this
central boss 5 is a plurality of similar bosses
8. As clearly shown in Figs. 2 and 3, these
bosses are annularly spaced about the edge
of the face plate so that when the massage 80
members 9 are threaded into these bosses
8, they will be spaced from the central mas-
sage member 7. Other ways of forming
these threaded openings in the face plate
will readily suggest themselves. Between 85

these spaces formed by the outer massage
members and the central massage nipple
7, the face plate 1 is provided with a series
of spray openings 10. By this arrange-
ment, the water spray through the face 90
plate will discharge between the massage
nipples and the full advantage of the spray
in connection with an extensive massaging
area can be secured. It is obvious that this
invention comprehends any arrangement of 95
the spray apertures in relation to the de-
tachable massaging device whereby these
massage members do not interfere with
the proper spray discharge.

Referring more particularly to the mas-
sage nipples, it will be seen that the central
and outer members are similarly construct-
ed, each including a threaded stem, a pref-
erably rubber body portion 11 formed with
depending massage fingers 12. In lieu of 105
the specific form of massage nipple shown
in Fig. 2, other types such as the sponge
shown in Fig. 4 may be substituted. This

device includes a threaded spindle 13 to which is attached a cap 14 formed with the sponge disk 15.

- A further feature of the invention comprises the means for providing the spray with a soap container so located that the water coming into the spray head from the water inlet discharges directly upon the soap within the container to provide a soapy spray. Various constructions may be used. In Fig. 5 is shown one means for carrying this out. In this embodiment, the central dome 3 is provided with a centrally arranged downwardly projecting flange 16 having an annular lip 17 on which is seated a flange 18 of the soap basket 19, which may be of wire mesh or any other open construction. The flange 18 is securely clamped in place by the threaded cap 20 so that the soap basket 19 may be removed if its use is not desired. It is obvious that this soap basket may be also detachably connected with the top of an imperforate dome, in which case, the back plate 2 would be detachably threaded to the face plate to permit the removal of the basket 19. It is furthermore evident that various means for locating this spray head within the basket may be used.
- 30 A device constructed as above combines all the features of the bath spray with a massage instrument. The construction described is particularly effective for the reason that the massaging nipples are removable and may be replaced when worn out or they may be replaced by other massaging or body contacting devices such as the sponge

shown in Fig. 4. It is furthermore evident that if the user wish to remove the central member 7, the opening in the central 40 boss 5 will permit a greater discharge of water therethrough while the concentric ring of massaging devices will be sufficient massaging area.

It is obvious that minor changes in the 45 details of construction may be made without departing from the spirit of the invention as set forth in the appended claims.

Having thus described the invention, what I claim as new and desire to secure 50 by Letters-Patent, is:—

1. A combined bath spray and massage device comprising a spray head including a face plate, a centrally located massage member detachably connected thereto, a plurality of massage members separately detachable from said plate and arranged in spaced relation about said central device, said plate having a series of spray openings intermediate said central and said spaced 55 members.

2. A combined bath spray and massage device comprising a spray head including a face plate having a central threaded opening, a plurality of threaded openings 65 arranged in spaced relation thereabout, a plurality of massage members provided with screw stems detachably threaded into said openings, said plate having a series of spray openings intermediate said threaded 75 openings.

In testimony whereof, I affix my signature.

PATRICK J. FITZGERALD.
